SELECTOR SYSTEM FOR RADIO RECEIVING APPARATUS

Lester L. Jones, Oradell, N. J.

Application December 31, 1927, Serial No. 243,790

22 Claims. (Cl. 250—40)

This invention relates to radio receiving apparatus, and relates more particularly to radio receiving apparatus in which the selection of the frequency and the amplification of the energy of the oscillations are effected by different systems; and has special reference to the provision of circuit coupling and tuning means in the selector system embodying improvements of the selector system set forth in my copending application Serial No. 205,935 filed July 15, 1927, since issued as Patent 1,850,754, dated March 22, 1932.

The ultimate object of the invention, as set forth in my aforesaid copending application, centers about the provision of a radio receiving apparatus in which the selection of the desired frequency is accomplished in geometric progression by means of three or more tuned circuits arranged in cascade, said circuits being devoid of separate energy sources so that the selection of the oscillations of the desired frequency is accomplished without energy amplification or relay action, this selective system being so organized that the full geometric selectivity of the system is realized or effectuated.

To accomplish this object, I have discovered that the selector system, devoid of electron discharge devices or separate energy sources, should be organized so as to constrain the flow of energy to move seriatum through the cascaded circuits of the selective system, the said circuits being, moreover, so inter-related as to prevent any but the first circuit of the series from receiving energy from an extraneous source. I have further discovered that these circuits of the selective system may be so coupled together and operated as to effect a maximum energy transfer with a minimum energy loss in the transmission of the energy; and that when so organized a maximum and full geometric selection of the energy is effected. In my aforesaid application Ser. No. 205,935, since issued as Patent 1,850,754, a selector system embodying this organization is described and claimed.

The improvements in this selector system which constitute the prime desiderata of my present invention reside in and center about the provision of a simplification of the coupling linkages between the tuned cascaded circuits, with a consequent simplification of the apparatus and of the energy transfer problems of the system. I have found that the coupling linkages between the circuits of the selector system may be inter-related in a manner to permit that constraining control of the energy flow through the sequential circuits of the system, as well as that coupling

control between the circuits, which have been found so desirable in producing the selective energy transmission and the production of the maximum energy transfer with the minimum energy loss aforesaid.

To the accomplishment of these objects and of such other objects as will hereinafter appear, my invention consists in the elements and their relation one to the other as hereinafter more particularly described and sought to be defined in the claims; reference being had to the accompanying drawings which show the preferred embodiment of my invention, and in which:

Fig. 1 is a wiring diagrammatic view of the improved selector system of my present invention showing the same in conventional circuit form, and

Fig. 2 is a diagrammatic view thereof exemplifying a preferred manner of organizing the parts in a commercially built radio receiving set, and

Fig. 3 is a diagrammatic view of a modification of the invention.

Referring now more in detail to the drawings, the selector system of the invention, generally designated as S, comprises three or more tuned or selective circuits S1, S2 and S3 coupled together inductively by variable coupling means M₁ and M₂, the first selector circuit S1 being coupled to an energy receptor such as the antenna A, and the last selector circuit S3 being coupled to the filament grid circuit of the first tube of an amplifier a.

In order to realize or effectuate the full selectivity in geometric progression of the selector system S, the selective circuits S1—S3 thereof should be so interrelated that the first and third circuits S1 and S3 be capacitively and inductively decoupled, this to constrain the energy to flow from the first to the third selective circuits of the series through the second or intermediate circuit of the series. The three or more cascaded selective circuits should be capacitively or inductively shielded from each other, except through the means M₁ and M₂ which couple the circuits together, this so that the second and third selective circuits S2 and S3 be prevented from receiving energy from any extraneous source. This inter-circuit shielding or decoupling except for the energy coupling means between the circuits is found to be very important in order to obtain the full system selectivity. For producing that coupling variation between the circuits which secures the maximum system selectivity with the minimum energy loss in the transmission of the

energy through the selector system and for effecting a volume variation over an extremely wide range, the variable coupling means M_1 and M_2 is constructed to permit a simultaneous variation in like degrees of the couplings between the selector circuits S_1-S_2 and S_2-S_3 , this being accomplished by operating the adjustable coupling means M_1 and M_2 from a single control element or dial 10 also designated as "coupling control".
10 Fig. 1 of the drawings shows the fundamental arrangement of the selector circuits of the system which permits the desired simplified control of both the coupling inter-linkages and the capacitive and inductive decoupling between the selector circuits of the system. The desired results are preferably secured by localizing the energy transfer linkages at or in the coupling means M_1 and M_2 , this being desirably obtained by localizing the inductive components of the terminal selector circuits S_1 and S_3 in the inductance coils L_1 and L_3 and by subdividing the inductance of the intermediate circuit S_2 into two components L_{21} and L_{22} , one for each of the coupling means M_1 and M_2 , the inductive components L_{21} and L_{22} being preferably made equal to each other. For simultaneously adjusting the couplings M_1 and M_2 , the inductive components L_{21} and L_{22} of the intermediate circuit, preferably separated a distance apart, are mounted so as to be movable simultaneously by means of a single control such as 10 into and out of coupling relation with the inductance coils L_1 and L_3 so that the means for simultaneously adjusting both of the coupling means M_1 and M_2 is associated wholly with the second or intermediate circuit of the series.

All of the circuits of the series are preferably made resonant and tunable to the desired selected frequency, the first selector circuit S_1 being provided for this purpose with the adjustable tuning condenser C_1 , the second and third selector circuits being correspondingly provided with the tuning condensers C_2 and C_3 . Each of these circuits is preferably grounded as shown by the conventional grounding g . The antenna A , described further hereinafter, is coupled capacitively by means of the condenser K to the first tuned circuit S_1 ; and where the tuning condensers C_1 , C_2 and C_3 are desired to be simultaneously adjusted for uni-control, the small fixed condensers 11 and 12 are arranged in parallel to the tuning condensers C_1 and C_2 in the first and intermediate circuits so as to raise the minimum circuit capacity of these circuits by an amount equal to the tube input capacity in parallel with the condenser C_3 . The inductive components of the three selector circuits are also equalized, the resultant of the inductive components L_{21} and L_{22} of the intermediate circuit being equal to the localized inductances L_1 and L_3 of the terminal circuits.

Referring now to Fig. 2 of the drawings, I show the circuit parts described in connection with Fig. 1 arranged in a receiving set assembly for the purpose of showing some of the advantages secured by the organization of the parts; the parts of Fig. 2 of the drawings which are similar to Fig. 1 being designated by similar reference characters. The three selector circuits are shieldingly enclosed in a metal container 13 connected to ground and to which one of the output leads 14 is connected, the input antenna lead 15 and one of the output leads 16 extending through the shield for connection to either the antenna A or A' and to the amplifier respectively.

To capacitively and inductively shield or decouple the circuits of the series except for the adjustable energy coupling means M_1 and M_2 , the two inductance coils L_1 and L_3 of the terminal circuits are made astatic and preferably embodying a construction such as is described and claimed in my patent to Coil system, No. 1,608,560 of Nov. 30, 1926, the construction being such that there is substantial freedom from magnetic and electrostatic coupling between these inductance coils. These inductance coils L_1 and L_3 , each comprising oppositely wound coaxial coils indicated in both Figs. 1 and 2 and specifically described in my aforesaid Patent No. 1,608,560, are spaced apart so as to further minimize the effect of any residual coupling which may exist therebetween. I have found that the effect of residuals in a selector system of the kind herein set forth is more severe than in ordinary tuned radio frequency circuits, since there are no separate sources of energy in the selector system S and therefore the energy received by the selector circuit S_3 is of the same order of magnitude as that transmitted by the selector circuit S_1 ; and to produce a substantially complete decoupling so as to constrain the energy to flow through the intermediate circuit of the series, I prefer to partition the construction by adding a shield plate 17 between the selector circuit S_1 and the remainder of the apparatus and by interposing a second shield plate 18 capacitively decoupling the tuning condenser C_2 from the tuning condenser C_3 . The tuning condensers C_1 , C_2 and C_3 may be connected for simultaneous adjustment by having the rotors thereof mounted on a single shaft and controlled from a single dial such as 19 also designated as "tuning control".

For simultaneously adjusting the couplings M_1 and M_2 , the inductance coils L_{21} and L_{22} of the intermediate circuit, located in the compartments of the terminal selector circuits and spaced a substantial distance apart, are mounted for movement or rotation on a single tubular shaft 20, the said shaft being desirably utilized as a connecting conductor between the capacitive and inductive components of the intermediate circuit S_2 , the same being grounded as shown at g . The other conductive connection 21 between the coils L_{21} and L_{22} of the intermediate circuit is preferably arranged within the tubular shaft 20 and is shielded thereby. To assist in producing the optimum inductive decoupling between the terminal circuits of the series and in further minimizing coupling to external fields which may penetrate the box 13, the two coils L_{21} and L_{22} are preferably constructed as an astatic pair, this being accomplished by arranging the windings of these coils in opposite relation or by connecting the terminals of these coils in circuit so as to produce oppositely directed instantaneous magnetic fluxes in the coils L_{21} and L_{22} .

By means of the construction thus far described, it will be seen that the inductive components of all of the three selector circuits are localized in the two coupling means M_1 and M_2 , with a resulting simplification not only of the inductance construction of the system, but of the energy transfer problems between the circuits. It will then be seen that by making the two inductances L_1 and L_3 astatic, and the two inductive components of the intermediate circuit as an astatic pair, and by separating these inductances in the manner set forth, small residuals are produced and the effect of these residuals is further minimized. It will further be

seen that to secure the optimum conditions found necessary in a system of this character, substantially complete decoupling, both capacitively and magnetically, may be effected by the additional 5 inter-circuit shielding. It will be understood, furthermore, that the coupling control is reduced to or localized in the intermediate circuit S2, resulting in further mechanical simplification. It will be further seen that the astatic coils L₁ and 10 L₃ are, in effect, shielded coils and more specifically comprise inductance coils which are almost completely shielded. With this construction the coil L₂₁ of the intermediate circuit is coupled to the leakage flux of the shielded coil L₁ and similarly the coil L₂₂ is coupled in like manner to the shielded coil L₃. The coils L₂₁ and L₂₂, however, are substantially completely shielded from each other by the shield plate or partition 17. With this system it is possible also to arrange the 15 whole coupling means with only one flexible lead, namely, the wire or conductor 22 joining the tuning condenser C₂ and the coil L₂₂, which flexible lead (at high potential) may be shielded by the grounded shielding tube 23.

20 As set forth in my aforesaid copending application, it will be further understood that by similarly adjusting the coupling instrumentalities M₁ and M₂, there is prevented a difference in degree of coupling between the circuits of the series, which difference in degree would result in a loss of selectivity of the system. This will be appreciated when it is seen that when a pair of the circuits is more tightly coupled than another pair, the loss in selectivity of the system due to 25 the tightly coupled pair is greater than the gain in selectivity which is due to the weakly coupled pair, so that for a given energy transmission the selectivity of the system as a whole is less than it would be where both pairs of circuits are coupled with equal degrees of coupling. Moreover, by utilizing a plurality of coupling instrumentalities and by effecting the simultaneous adjustment of such coupling instrumentalities, I produce an exceedingly wide coupling and volume range of the circuits. The organization of 30 the coupling instrumentalities results in that decoupling between the individual circuits which is desired for effecting a constraining of the flow of energy through the consecutive circuits to be progressively acted upon by each of the circuits of the series, this providing the successful solution of the problem of building a selector system which is adapted to produce selectivity in true geometric progression and which is adapted for 35 circuit attachment to a separate audion amplifier system of the untuned type.

The antenna system with which the selector system is employed may be a simple antenna, such as A' heretofore referred to, connected by 40 means of the coupling condenser K' to the first selector circuit S1. I prefer, however, to employ an improved antenna system A shown in Figs. 1 and 2 of the drawings, which is described and claimed in an application for Letters Patent filed of even date herewith, Serial No. 243,789, since issued as Patent 1,761,211, dated June 3, 45 1930, and which comprises an antenna inductance L made up of two parts 24 and 25 separated by a tap 26 which is connected to a switch means 50 27, said switch means being arranged in parallel to the inductance section 25, which latter section is connected to ground g by way of the series tuning condenser C. Where the selector system is 55 shielded as shown in Fig. 2 of the drawings, the inductance L need not be enclosed in a separate

metal shield; but where, as shown in Fig. 1 of the drawings, no separate shield is provided for the selector circuits, the inductance L is enclosed in a separate metal container 28 to prevent any direct coupling between it and the intermediate circuit of the series. The tuning of the antenna circuit is accomplished by the rotation of the variable condenser C, and this condenser controls the opening and closing of the switch 27 by an element 29 which forms part of the rotor of the condenser C. During rotation of the condenser C through one-half of its revolution, element 29 is disengaged from the switch 27, so that the whole coil L of the antenna is in circuit, and during rotation of the condenser through the remaining one-half of its revolution the element 29 engages the switch 27 to close the same, as shown in the drawings, and the section 24 only of the antenna inductance L is now in circuit through the tuning range. With this construction a series tuned antenna may be used efficiently for the entire broadcast receiving range.

As an example of suitable magnitudes which may be employed for the constants of the circuits 100 to produce the intended results, the maximum capacity of the antenna tuning condenser C may be 100 micro-micro-farads, the maximum capacity of the tuning condensers C₁, C₂ and C₃ may be 500 micro-micro-farads, the capacity of the 105 coupling condenser K may be 3 micro-micro-farads, the antenna inductance L may be 1.1 milihenrys; the astatic coils L₁ and L₃ are equal to each other and equal to the sum of the astatic 110 pair of coils L₂₁ and L₂₂, and the mutual inductances of M₁ and M₂ are equal to one another for all settings.

In Fig. 3 I show a modified form of the invention in which four tuned circuits in lieu of three tuned circuits are employed. To accomplish this 115 the intermediate circuit S2 is subdivided into two similar tuned circuits. The first and third or external circuits S1 and S3 are substantially the same as that shown in Fig. 1 of the drawings, and are indicated by similar reference characters. 120 The inductive component of the intermediate circuit S2 is subdivided in substantially the same manner as that heretofore described, but the same is subdivided into components for the two tuned circuits. Thus the inductive component of 125 this generalized intermediate circuit S2 is subdivided into the two inductance coils L₂₁ and L₂₂, the first for the coupling M₁ and the second for the coupling M₂, the inductive component, however, being further provided with two coils L^a and L^b which are small fractions of the inductance 130 of the coils L₂₁ and L₂₂ and are coupled very tightly together on the shaft 20', which shaft is connected to the coils L₂₁ and L₂₂ in the manner disclosed in Fig. 2 of the drawings. The connections between all of the coils in this intermediate circuit are fully indicated in Fig. 3 of the drawings, and as shown, the coils L^a and L^b are inductively but may be conductively coupled and are affixed so as to be rotatable with the shaft 20'. It will be manifest that there is no change in the 135 coupling between these small coil sections L^a and L^b. These coils are partially shielded by the cylindrical passage O through the wall 17' which is equivalent to the wall 17 of the structure shown in Fig. 2 of the drawings. These coils L^a and L^b are coupled so as to give a coupling coefficient between the circuits of L₂₁ and L₂₂ substantially 140 equal to the maximum coupling available in the other coupling units.

The two tuned circuits for the generalized in- 150

termediate circuit S2 are provided by the tuning condenser C_{21} associated with the coil L_{21} and the tuning condenser C_{22} associated with the coil L_{22} . The circuit connections are as shown in Fig. 3 of the drawings, and similar to that heretofore described. For the reasons aforesaid, the small condensers $12a$ and $12b$ are connected in parallel with these tuning condensers.

The operation of the selector system of my present invention and the many advantages thereof will in the main be fully apparent from the above detailed description thereof. It will be further apparent that while I have shown and described my invention in its preferred form, many changes and modifications may be made in the structure disclosed without departing from the spirit of my invention, defined in the following claims.

1. I claim:

1. A system for selecting in geometric progression electrical oscillations of a given frequency from oscillations differing therefrom in frequency comprising at least three circuits of low decrement resonant to the frequency of the oscillations to be selected and arranged in cascade or series; a first coupling means linking the first circuit of the series to the second or intermediate circuit solely by leakage flux for the transfer to the second circuit of energy selected by the first circuit, and a second coupling means linking the second or intermediate circuit of the series to the third circuit solely by leakage flux for the transfer to the third circuit of energy selected by the second circuit, the inductive components of said first and third circuits being substantially localized respectively in said first and second coupling means and the inductance of said intermediate circuit being divided into two components, one component for each of the said coupling means.

2. A system for selecting in geometric progression electrical oscillations of a given frequency from oscillations differing therefrom in frequency comprising at least three circuits of low decrement resonant to the frequency of the oscillations to be selected and arranged in cascade or series, a first variable coupling means linking the first circuit of the series to the second or intermediate circuit solely by leakage flux for the transfer to the second circuit of energy selected by the first circuit, a second variable coupling means linking the second or intermediate circuit of the series to the third circuit solely by leakage flux for the transfer to the third circuit of energy selected by the second circuit, the inductive components of said first and third circuits being substantially localized in said coupling means and the inductance of said intermediate circuit being divided into two components, one component for each of the said coupling means, and means for simultaneously similarly adjusting both of said variable coupling means.

3. A system for selecting in geometric progression electrical oscillations of a given frequency from oscillations differing therefrom in frequency comprising at least three circuits of low decrement, resonant to the frequency of the oscillations to be selected and arranged in cascade or series, a first coupling means linking the first circuit of the series to the second or intermediate circuit solely by leakage flux for the transfer to the second circuit of energy selected by the first circuit, a second coupling means linking the second or intermediate circuit of the series to the third circuit solely by leakage flux for the transfer to the third circuit of energy selected by the second circuit, the inductive components of said first and third circuits being substantially localized in said coupling means and the inductance of said intermediate circuit being divided into two components, one component for each of the said coupling means.

for the transfer to the third circuit of energy selected by the second circuit; the inductive components of said first and third circuits being substantially localized in said coupling means and the inductance of said intermediate circuit being divided into two equal and separated components, one component for each of the said coupling means, and means for tuning each of said circuits. 80

4. A selective system comprising at least three circuits of low decrement arranged in cascade or series and tunable to a given frequency of oscillation, a first coupling means linking the first circuit of the series to the second or intermediate circuit, said first coupling means comprising a substantially astatic inductance coil in the first circuit and a coil in the second circuit linked thereto solely by leakage flux, a second coupling means linking the second or intermediate circuit of the series to the third circuit, the said second coupling means comprising a substantially astatic coil in said third circuit and a second coil in said intermediate circuit linked thereto solely by leakage flux, the inductances of the two coils of the intermediate circuit being substantially equal. 85

5. A selective system comprising at least three circuits of low decrement arranged in cascade or series and tunable to a given frequency of oscillation, a first variable coupling means linking the first circuit of the series to the second or intermediate circuit, said first coupling means comprising a substantially astatic inductance coil in the first circuit and a coil in the second circuit linked thereto solely by leakage flux, a second variable coupling means linking the second or intermediate circuit of the series to the third circuit, the said second coupling means comprising a substantially astatic coil in said third circuit and a second coil in said intermediate circuit linked thereto solely by leakage flux, the inductances of the two coils of the intermediate circuit being substantially equal, 90 and means for simultaneously and equally adjusting both of said variable coupling means. 100

6. A selective system comprising at least three circuits of low decrement arranged in cascade or series and tunable to a given frequency of oscillation, a first coupling means linking the first circuit of the series to the second or intermediate circuit, said first coupling means comprising a substantially astatic inductance coil in the first circuit and a coil in the second circuit linked thereto solely by leakage flux, a second coupling means linking the second or intermediate circuit of the series to the third circuit, the said second coupling means comprising a substantially astatic coil in said third circuit and a second coil in said intermediate circuit linked thereto solely by leakage flux, the inductances of the two coils of the intermediate circuit being substantially equal, 105 and the inductances of the two coils of the intermediate circuit being substantially equal, and means for simultaneously and equally adjusting both of said variable coupling means. 110

115

7. A selective system comprising at least three circuits of low decrement arranged in cascade or series and tunable to a given frequency of oscillation, a first coupling means linking the first circuit of the series to the second or intermediate circuit, said first coupling means comprising a substantially astatic inductance coil in the first circuit and a coil in the second circuit linked thereto solely by leakage flux, a second coupling means linking the second or intermediate circuit of the series to the third circuit, the said second coupling means comprising a substantially astatic coil in said third circuit and a second coil in said intermediate circuit linked thereto solely by leakage flux, the inductances of the two coils of the intermediate circuit being substantially equal and the inductance of said first and third circuits being substantially localized in said astatic coils. 120

125

130

135

140

145

150

- comprising a substantially astatic coil in said third circuit and a second coil in said intermediate circuit linked thereto, the two coils of the intermediate circuit comprising in combination 5 an inductance astatic with respect to the signal wave field.
8. A selective system comprising at least three circuits arranged in cascade or series and tunable to a given frequency of oscillation, a first variable coupling means linking the first circuit of the series to the second or intermediate circuit, said first coupling means comprising a substantially astatic inductance coil in the first circuit and a coil in the second circuit linked thereto, a 10 second variable coupling means linking the second or intermediate circuit of the series to the third circuit, the said second coupling means comprising a substantially astatic coil in said third circuit and a second coil in said intermediate 15 circuit linked thereto, the two coils of the intermediate circuit comprising in combination an inductance astatic with respect to the signal wave field and being equal in inductance, and means for simultaneously and equally moving 20 said astatic pair of coils to simultaneously adjust both of said variable coupling means.
9. A selective system comprising a plurality of tuned circuits arranged in series and including terminal circuits and an intermediate circuit, 25 and means for linking said intermediate circuit to said terminal circuits comprising a pair of spaced apart inductance coils one in each of said terminal circuits and a pair of inductance coils in said intermediate circuit spaced apart and 30 coupled to the aforesaid inductance coils of said terminal circuits, said pair of coils in the intermediate circuit comprising in combination an inductance astatic with respect to the signal wave field.
- 40 10. A selective system comprising a plurality of tuned circuits arranged in series and including terminal circuits and an intermediate circuit and means for linking said intermediate circuit to said terminal circuits comprising two spaced apart inductance coils one in each of said terminal circuits and a pair of inductance coils in 45 said intermediate circuit spaced apart and coupled to the inductance coils of said terminal circuits, and means connecting the said pair of inductance coils, said connecting means consisting of a tubular shaft connected in grounded 50 circuit with the coils and a connecting conductor within said tubular shaft.
11. A selector system comprising at least three 55 circuits of low decrement resonant to the frequency of the oscillations to be selected and arranged in cascade or series, each of said circuits embodying inductance and capacity components forming a closed oscillating circuit, a first coupling means linking the first circuit of the series to the second or intermediate circuit solely by leakage flux for the transfer to the second circuit of energy selected by the first circuit, a second coupling means linking the second or intermediate circuit of the series to the third circuit solely by leakage flux for the transfer to the third circuit of energy selected by the second circuit, the inductive components of the first and third circuits being substantially localized 65 respectively in said first and second coupling means, and means for simultaneously adjusting the tuning of said three resonant circuits.
12. A selector system comprising at least three 70 circuits of low decrement resonant to the frequency of the oscillations to be selected and ar-
- ranged in cascade or series, each of said circuits embodying inductance and capacity components forming a closed oscillating circuit, a first coupling means linking the first circuit of the series to the second or intermediate circuit solely by leakage flux for the transfer to the second circuit of energy selected by the first circuit, a small series condenser for loosely capacitively coupling the first circuit of the series to an energy receptor, a second coupling means linking the second or intermediate circuit of the series to the third circuit solely by leakage flux for the transfer to the third circuit of energy selected by the second circuit, the inductive components of the first and third circuits being substantially localized respectively in said first and second coupling means and the inductance of said intermediate circuit being divided into two components, one component for each of said coupling means, and means for simultaneously adjusting the tuning of said three resonant circuits.
13. The selector system of claim 11 in which the capacity components of the three circuits comprise the tuning means, and condensers in parallel with the capacity tuning means of the first and second circuits to raise the minimum circuit capacity thereof by an amount equal to the tube input capacity of a tube to which the third circuit of the series is connectible.
14. A system for selecting electrical oscillations of a given frequency from oscillations differing therefrom in frequency comprising four closed circuits of low decrement resonant to the frequency of the oscillations to be selected and arranged in cascade or series, each of said circuits embodying capacitive and inductive components, a first energy transfer inductive coupling means linking the first circuit of the series to the second circuit, a second energy transfer inductive coupling means linking the third circuit of the series to the fourth circuit, and energy transfer means coupling the second and third circuits together, the inductive components of all of the four circuits being substantially localized in said first and second inductive coupling means.
15. The system of claim 14 in which the energy transfer means coupling the second and third circuits together comprises inductance elements tightly coupled together having a value which is a small fraction of the inductance magnitude of the second and third circuits, thereby providing only a loose coupling between the circuits, despite close juxtaposition of the inductance elements.
16. The system of claim 14 in which the inductive components of the first and fourth circuits are substantially astatic coils, whereby the coupling thereto is solely by means of leakage flux.
17. A selective system comprising at least three 135 circuits arranged in cascade or series and tunable to a given frequency of oscillation, a first coupling means linking the first circuit of the series to the second or intermediate circuit, said first coupling means comprising an almost completely shielded inductance coil in the first circuit and a coil in the second circuit coupled to the leakage flux of the shielded coil, a second coupling means linking the second or intermediate circuit of the series to the third circuit, the said second coupling means comprising an almost completely shielded inductance coil in said third circuit and a second coil in said intermediate circuit linked thereto.
18. A selective system comprising at least three 140 circuits arranged in cascade or series and tunable to a given frequency of oscillation, a first coupling means linking the first circuit of the series to the second or intermediate circuit, said first coupling means comprising an almost completely shielded inductance coil in the first circuit and a coil in the second circuit coupled to the leakage flux of the shielded coil, a second coupling means linking the second or intermediate circuit of the series to the third circuit, the said second coupling means comprising an almost completely shielded inductance coil in said third circuit and a second coil in said intermediate circuit linked thereto.

to a given frequency of oscillation, a first coupling means linking the first circuit of the series to the second or intermediate circuit, said first coupling means comprising an almost completely shielded inductance coil in the first circuit and a coil in the second circuit linked to the leakage flux of the shielded coil, a second coupling means linking the second or intermediate circuit of the series to the third circuit, the said second coupling means comprising an almost completely shielded inductance coil in said third circuit and a second coil in said intermediate circuit linked thereto, and means for substantially completely shielding the two coils of the intermediate circuit from each other.

19. The system of claim 14 in which each of the four circuits is a closed tuned circuit the first one of which is combined with a small series condenser for loosely capacitively coupling the first closed tuned circuit to an antenna.

20. The system of claim 14 in which the first and second energy transfer coupling means each comprises inductance coils at least one of which is so shielded that the inductance coils are coupled solely by leakage flux and in which the inductance coils of the second and third circuit are substantially completely magnetically decoupled one from the other.

21. The system of claim 14 in which the first and second energy transfer coupling means each comprises inductance coils at least one of which

is so shielded that the said inductance coils are coupled solely by leakage flux, in which the inductance coils of the second and third circuits are substantially completely magnetically decoupled one from the other, and in which the energy transfer means coupling the second and third circuits together comprises an inductance coil which is a small fraction of the inductance magnitude of the second and third circuits and which tightly couples a portion of one of these circuits to the other.

22. A system for selecting electrical oscillations of a given frequency from oscillations differing therefrom in frequency comprising four closed circuits of low decrement tunable to the frequency of the oscillations to be selected and arranged in cascade or series, each of said circuits embodying capacitive and inductive components, a first energy transfer inductive coupling means linking the first circuit of the series to the second circuit, a second energy transfer inductive coupling means linking the third circuit of the series to the fourth circuit, energy transfer means coupling the second and third circuits together, the inductive components of all of the four circuits being substantially localized in said first and second inductive coupling means, and uni-control means for simultaneously and equally varying the tuning of all four circuits.
